CLAIM

The ornamental design for a notebook computer having a key, as shown and described.

DESCRIPTION

FIG. 1 is a top-right front perspective view of the notebook computer having a key according to the claimed design, with the notebook computer in an open position;

FIG. 2 is a top-left front perspective view of the notebook computer having a key according to the claimed design, with the notebook computer in an open position;

FIG. 3 is a front view of the notebook computer having a key according to the claimed design, with the notebook computer in the open position;

FIG. 4 is a rear view of the notebook computer having a key according to the claimed design, with the notebook computer in the open position;

FIG. 5 is a top view of the notebook computer having a key according to the claimed design, with the notebook computer in the open position;

FIG. 6 is a bottom view of the notebook computer having a key according to the claimed design, with the notebook computer in the open position;

FIG. 7 is a left side view of the notebook computer having a key according to the claimed design, with the notebook computer in the open position;

FIG. 8 is a right side view of the notebook computer having a key according to the claimed design, with the notebook computer in the open position;

FIG. 9 is an enlarged, top view of the notebook computer having a key according to the claimed design, with the notebook computer in the open position;

FIG. 10 is an enlarged, top-right front perspective view of the notebook computer having a key according to the claimed design, with the notebook computer in the open position; and,

FIG. 11 is an enlarged, top-left front perspective view of the notebook computer having a key according to the claimed design, with the notebook computer in the open position. The broken lines in FIGS. 1-11 depict portions of the notebook computer that form no part of the claimed design. The arrows, leaders, and characters "A" and "B" in FIG. 5 show the enlarged range for FIG. 9 and form no part of the claimed design.

1 Claim, 11 Drawing Sheets
